ATTORNEY

UNITED STATES PATENT OFFICE.

CHARLES S. SHEPARD, OF CATTARAUGUS, NEW YORK.

DETACHABLE PAIL-COVER.

1,242,378.

Specification of Letters Patent.

Patented Oct. 9, 1917.

Application filed November 13, 1915. Serial No. 61,428.

To all whom it may concern:

Be it known that I, CHARLES S. SHEPARD, a citizen of the United States of America, and a resident of the village of Cattaraugus, 5 county of Cattaraugus, and State of New York, have invented certain new and useful Improvements in Detachable Pail-Covers, of which the following is a full, clear, and exact description.

10 My invention relates generally to pail covers, and more particularly to covers which may be used for milk receptacles in dairies.

It is well known that many pails now 15 used for this purpose are provided with covers which partially envelop the top of the pail, thus leaving a pouring opening. Such covers are not detachable, but are secured to the top of the pail, usually by 20 means of solder. Inasmuch as such permanently secured covers cannot be detached from the pail each time the same is used, there are numerous pockets and crevices which cannot be, by any practical means, 25 thoroughly cleansed. These pockets provide places for the lodgment of dirt and foreign substances, and thus make these pails very unsanitary.

The general object of my invention, therefore, 30 has been to provide a cover for such pails which can be easily detached each time the pail is used, so that not only the pail, but the cover may readily be made sanitary.

Another object has been to provide a cover 35 which shall be simple and cheap to manufacture and one which may be quickly and securely attached to the pail.

I have accomplished the above objects and 40 advantages by the device shown in the accompanying drawing, in which:

Figure 1 is a side elevation of a pail with my cover attached and showing the cover in section.

Fig. 2 shows an enlarged bottom view of 45 my cover.

Fig. 3 shows an enlarged, fragmentary, sectional elevation of the cover fastening means.

In the drawings, 5 represents a pail having 50 the usual beaded and wired rim 6. 7 is my pail cover, which preferably has the same diameter as the diameter of the rim 6 of the pail.

My cover is circular in its general contour and slopes from the center toward the outer edge thereof. At one point in the

circumference, the cover is cut away so that when attached to the pail the pouring opening 8 is provided. This opening is bounded by a circular rim 9, which is preferably beaded and provided with an inclosed wire. The outer rim 10 of the cover is preferably turned over, as clearly shown in Fig. 3, thus providing a stiff and strong construction.

Arranged about the outer rim 10 of the cover are a plurality of clips 11, 12, 13 and 14. These clips are secured to the upper face of the cover and have outwardly extending and inwardly turned lips 15 for engagement with the beaded rim 6 of the pail. The clips 13 and 14 are each arranged on opposite sides of the opening 8 and near the edge 9 so as to hold the points 16 and 17, which are formed at the intersection of the rims 9 and 10, securely in place. 75

The wire placed in the edge 9, surrounding the opening 8, is preferably of resilient material so that the points 16 and 17 will be drawn toward each other. An additional spring, preferably in the form of a brass wire 18, is provided.

This wire is preferably curved and has its ends secured to the under side of the cover near the points 16 and 17. This spring 18 acts with the wire in the edge 9 to draw the points 16 and 17 toward each other and hold them under spring tension so that when the points are spread in placing them over the beaded rim of the pail, the cover will be securely held in position by the resilience 90 of the spring 18 and wire in the edge 9. 85

When my cover is to be secured to the pail, the points 16 and 17 are raised as the center of the top of the cover is slightly pressed, thus increasing the distance between the corners, and when in this position the clips 11 and 12 are engaged with the rim of the pail and the points 16 and 17 brought down on top of the rim, and when released the clips 13 and 14 will be drawn inwardly and also engage with the beaded rim 6 of the pail, thus securely holding the cover in position. When it is desired to release the cover, it is pressed downwardly at the central, top portion, which causes the points 16 and 17 to 100 be spread, whereupon they are lifted from engagement with the rim, thereby releasing the cover. 95

Obviously, some modification of the cover herein shown and described may be made 110 without departing from the spirit of my invention or the scope of the appended claims,

and I do not wish to be limited to the exact embodiment herein shown and described.

Having thus described my invention, what I claim is:

- 5 1. A resiliently-detachable pail cover so formed as to envelop a part of the top of a pail and leave a pouring opening therefor, means for engaging the rim of the said pail, and resilient means integral with said cover 10 for contracting the rim of the cover.
2. A resiliently-detachable pail cover so formed as to envelop a part of the top of a pail and leave a pouring opening therefor, clips carried by the cover for engaging the 15 beaded rim of the pail, and resilient means integral with said cover for contracting the rim of the cover.
3. A resiliently-detachable, crescent-shaped pail cover so formed to envelop a part 20 of the top of a pail and leave a pouring opening therefor, means for engaging the rim of the pail, and a spring normally under tension and having its ends secured to the cover near the point of the crescent 25 for drawing the points toward each other.
4. The combination with a pail, of a resiliently-detachable cover, said cover being so

formed as to envelop the greater part of the top of said pail, the edge of said cover which bounds the opening being beaded and 30 provided with a resilient wire, resilient means integral with said cover for contracting the rim of the cover, and means carried by said cover for engaging the rim of said pail.

35 5. The combination with a pail, of a resiliently-detachable, crescent-shaped cover, said cover being so formed as to envelop a part of the top of said pail, the edge of said cover, which bounds the opening, being 40 beaded and provided with a resilient wire, a spring normally under tension and having its ends secured to the cover near the points of the crescent for drawing the points toward each other, and means carried by said 45 cover for engaging the rim of said pail.

In testimony whereof, I have hereunto signed my name in the presence of two subscribing witnesses.

CHARLES S. SHEPARD.
